UNITED STATES PATENT OFFICE

2,255,300

FUSE CONSTRUCTION

William O. Schultz, South Milwaukee, Wis., assignor to Line Material Company, South Milwaukee, Wis., a corporation of Delaware

Application August 14, 1939, Serial No. 290,033

15 Claims. (Cl. 200—114)

This invention relates to a fuse construction. Objects of this invention are to provide a housed type of fuse in which the door protects the inside of the housing at all times even after the fuse has blown, and to provide such a construction in which the fuse tube moves out of circuit and the door moves to an angular position without moving completely away from the housing, thereby still acting as a door to prevent entrance of snow or rain and protecting the inside of the housing.

Further objects are to provide a housed type of expulsion fuse in which the fuse is supported by a lever from the lower support and is both pivotally and slidably joined to the lever so that the lever and fuse together constitute a link structure allowing the lower end of the fuse tube to move outwardly and the link structure to elongate itself without detaching the upper end of the fuse tube from the upper stationary contact.

Further objects are to provide a fuse construction in which the fuse tube and door form an assembly and are pivotally supported by a double hinge construction from the lower support and are spring urged outwardly, and in which a contact finger is spring urged into contact engagement with the lower terminal, said contact finger maintaining contact with the lower terminal for a material length of time while the fuse tube is moving outwardly to thereby allow the tube to clear itself prior to the breaking of the connection between the contact finger and the lower terminal, and to provide a construction whereby a portion of the link mechanism acts as a stop to limit the motion of the contact finger when the fuse tube and door assembly are removed from the housing, but in which such portion of the link mechanism moves out of the way when the fuse blows to allow unhampered motion of the contact finger.

Further objects are to provide a construction in which the door remains in position to protect the inside of the housing after the fuse blows, and in which the door and fuse tube assembly may be readily detached from the housing for refusing and after refusing, may be again positioned for pivotal support from the housing and may then be rocked into operative position.

An embodiment of the invention is shown in the accompanying drawings, in which:

Figure 1 is a view partly in section showing the fuse in closed position.

Figure 2 is a view similar to Figure 1 showing the position of the parts after the fuse has blown.

Figure 3 is a detail looking from the inside

towards the lower portion of the door and fuse assembly with the door and fuse assembly removed from the housing.

Referring to the drawings, it will be seen that 5 the device comprises a housing 1 of porcelain or other suitable insulating material and a door 2 of a phenolic condensation compound or other suitable material, such door being provided with an eyelet or handle portion 3. The housing is adapted to be positioned in either a vertical position or in a slanting position with the upper end projecting outwardly beyond the lower end and is carried from a suitable support not shown.

The housing is provided with upper and lower 15 stationary contacts having terminal portions 4 and 5 respectively, adapted to receive line wires which pass through apertures in the side walls not shown. The upper terminal also includes a contact brush 6 and a pair of resilient, outwardly extending arms 7 which form a U-shaped structure and which have outer, downwardly extending end portions 8 provided with downwardly and outwardly slanting cam faces 9.

The lower stationary contact includes the terminal portion 5 and a flat contact face 10 presented towards the front of the housing. A suitable barrier 11 is located between the upper and lower terminals in accordance with the usual construction, and the lower portion of the box 20 or housing has an open portion 12 directly below the lower open end of the fuse tube 13. The lower supports 14 are rigidly carried by the housing and may be supported directly from the back wall of the housing or from an extended portion 35 of the back wall as shown at 15. These lower supports 14 are provided with hook portions 16 which removably receive the outwardly projecting trunnions 17 of a lower supporting lever 18.

The lever 18 may be of somewhat channel 40 shape as shown and may have a transverse web 19 extending to approximately its upper end. The upper end of the lever is in the form of spaced, upwardly extending arms 20 which are slotted as indicated at 21 and are each provided 45 with outwardly projecting stops or fingers 22. The lower end of the lever is provided with an abutment 23 which normally is held in engagement with the fuse tube by means of the fuse link as shown in Figure 1.

The lever is provided with a threaded shank 24 and a thumb nut 25 for clamping the flexible leader 26 of the fuse link in place.

The fuse link may be of any suitable type. For example as shown, it may have the flexible leader 26 and a reduced fusible portion 27 and

an upper button-head which is clamped between the removable screw cap 28 and the upper terminal portion 29 of the fuse tube. This upper terminal portion 29 is provided with a forwardly projecting extension 30 that normally bears against the inner face of the door. It is provided with a flattened, downwardly extending portion 31 on its rear side against which the spring brush 6 bears. The door is provided with a pair of outwardly bowed cam members 32 which are provided with the spreader portions or cam portions 33, see Figure 2, which are adapted to spread the springy upper arms 7 when the door is manually pulled open.

The upper terminal 29 of the fuse tube is provided with pins 34 which project outwardly on opposite sides and which are normally in engagement with the cam faces 9 of the downwardly extending extensions 8 of the arms 7. However, when the door is manually pulled open, these cam members 33 spread the portions 8 of the arms 7 and allow the pins 34 to pass outwardly from between the spring arms 7. The construction is quite similar to that shown in the Schultz and Steinmayer Patent No. 2,029,593 of February 4, 1936.

The fuse tube 18 is provided with a block or member 35 rigidly secured thereto and pivotally joined to a pair of inwardly projecting arms 36 carried by the door. The pivotal connection is afforded by the screw or bolt 37. The member 35 has a pair of spaced, downwardly extending arms 38 which terminate in inwardly and downwardly slanting arms 39 which constitute stops for engagement with the web 19 of the lever 18 to limit the outward motion of the fuse tube and door assembly, as shown in Figure 2, after rupture of the fuse link.

The arms 38 carry a pivot pin 40 which is positioned within the slots 21 in the arms 20 of the lever 18 and which also pivotally carry a contact finger 41, such contact finger being provided with a pair of downwardly extending arms 42 through which the pin 40 passes to thus pivotally support the contact arm 41.

This contact finger 41 has a wide bearing face that bears directly against the face 10 of the lower stationary contact, as shown in Figure 1, and is provided with a shouldered portion 43 which is normally positioned above the fingers 22 of the lever 18, as shown in Figure 1.

A spring 44 is loosely coiled about the pin 40 and urges the contact finger or lever 41 in a counterclockwise direction, as viewed in Figures 1 and 2. If desired, the contact finger 41 may be provided with a strengthening rib on its upper side, but its contact face is extended transversely and has a wide bearing contact with the face 10 of the lower terminal.

The door is provided with a spring 45 which bears against the lower portion of the fuse tube and tends to rock the fuse tube in a clockwise direction about the pivot pin or screw 37 to thereby hold the stop 30 at the upper contact of the fuse tube against the door 2.

Assume that the parts are in the operative position as shown in Figure 1, and that an overload occurs. The fuse link is ruptured and the lever 18 withdraws any remaining portion of the fuse link, in addition to the expulsion action that occurs within the fuse tube. The lower end of the fuse tube and door assembly start to rock outwardly and the contact finger 41 maintains contact with the contact face 10 of the lower stationary contact for a material length of time

during the early portion of the outward rocking of the lower end of the fuse tube and door assembly, thereby allowing adequate time for the tube to clear itself even under light overloads. 5 The fuse tube and door assembly are urged towards outward rocking motion by means of the upper spring brush 6 and the spring urged contact finger 41, gravity also assisting in this operation when the device is mounted in a slanting position. 10 The shoulder 43 of the spring urged contact finger bears against the stops 22 of the lever 18 and urges the lever downwardly with reference to the fuse tube, in addition to the action of the upper spring brush 6, thus urging the 15 fuse tube and door assembly towards the position shown in Figure 2. The pin 40 freely slides in the slots 21 of the lever 18.

It is to be particularly noted that after the fuse tube and door assembly has moved to its slanting position which it occupies after rupture of the 20 fuse link, the contact finger 41 is out of contact with the lower contact, see Figure 2.

This construction therefore provides an extensible linkage mechanism constituted jointly of the 25 slotted lever 18 and the fuse tube, such jointed linkage construction being held at its upper and lower ends but free to pivot about such ends to the position shown in Figure 2, the extensibility of the linkage construction permitting such outward motion of the lower end of the fuse tube and door assembly. However, the outward motion of the parts is arrested when the fingers 39 engage the web 19 of the lever 18 as shown in 30 Figure 2, and thus the door is prevented from opening completely and exposing the interior of the housing. Instead it forms an outwardly slanting snow shed or rain shed and thus protects the interior of the housing. However, the fuse tube is taken out of circuit, for connection 35 with the lower stationary contact has now been broken.

In refusing, it is merely necessary to pull the 40 door open and lift the fuse tube and door assembly from the hooks or lower support 16. Thereafter a new fuse link is substituted for the burned 45 fuse link and the operator then rocks the contact finger 41 upwardly in a clockwise direction about the pivot pin 40 and thereafter moves the lever 18 upwardly to the position shown in Figure 1 and 50 attaches the flexible leader to the lever by means of the thumb nut 25.

The operator then releases the contact finger 41 and such finger can move inwardly a slight distance due to the slight spacing of the shoulder 55 43 from the stops or fingers 22 of the lever 18 as shown in Figure 1. He then replaces the trunnions in the hooks 16 and rocks the door to closed position. The contact finger 41 then yieldingly and firmly engages the face 10 of the lower stationary contact and the cam members 33 spread the portions 8 of the latch 7 and allow the trunnions to pass between the fingers 8, the fingers 8 thereafter moving towards each other and the pins 34 being then positioned rearwardly of the 60 downwardly slanting faces 9. The spring brush 6 yieldingly and firmly engages the portion 31 of the upper contact on the fuse tube and urges the fuse tube and door assembly outwardly to its final position as shown in Figure 2. When the 65 fuse tube and door assembly have moved outwardly as shown in Figure 2, the contact finger has moved completely away from the lower stationary contact and the lower supports 14 are electrically dead.

70 It will be seen that a novel form of fuse con-

struction has been provided in which advantage is taken of the idea of taking the fuse tube out of circuit after blowing by interrupting the circuit connection from the lower stationary contact to the lower contact of the fuse tube, but in which the door is not allowed to drop completely open but stays in such position as to adequately protect the interior of the housing.

It will also be seen that the fuse construction is effective in its operation and provides a positive interruption of the circuit upon either large or small overloads, and under either condition withdraws any remaining portion of the fuse link.

Although this invention has been described in considerable detail, it is to be understood that such description is intended as illustrative rather than limiting, as the invention may be variously embodied and is to be interpreted as claimed.

I claim:

1. A fuse construction comprising a first and second stationary contact, a support, a fuse tube and lever assembly constituting jointly link mechanism, said assembly being movably held by said first stationary contact and pivoted to said support and having a portion movable outwardly intermediate said first stationary contact and support, a movable contact carried by said link mechanism normally engaging said second stationary contact and movable outwardly with reference to said second stationary contact, a fuse link within said fuse tube normally restraining the outward motion of said link mechanism and electrically joining said stationary contacts through the agency of said movable contact, and a stop normally out of engagement with said lever and coming into contact with said lever when said fuse link is ruptured.

2. A fuse construction comprising a housing having an upper and a lower stationary contact and having a lower support, a fuse tube having upper and lower contacts engaging the upper and lower stationary contacts respectively, a fuse link within said fuse tube joining the upper and lower contacts of said fuse tube, a lever pivotally mounted on said support and on said fuse tube and being normally restrained by said fuse link, said fuse tube being movable outwardly adjacent its lower portion upon rupture of said fuse link to move the lower contact of the fuse tube out of engagement with the lower stationary contact, and means for limiting the outward motion of said fuse tube to maintain contact between the upper contact of said fuse tube and the upper stationary contact.

3. A fuse construction comprising a housing having an upper and a lower stationary contact, a fuse tube and door assembly, said fuse tube having an upper contact normally movably connected to the upper stationary contact and having a lower contact normally engaging the lower stationary contact, a support carried by said housing, a lever pivoted on said support and pivoted to said fuse tube, a fuse link normally electrically connecting the upper and lower contacts of said fuse tube and restraining said lever against motion with reference to said fuse tube, the lower portion of said fuse tube and door assembly and the lower contact of said fuse tube being movable outwardly upon rupture of said fuse link, and means carried by said fuse tube and normally out of contact with said lever for limiting the outward motion of said fuse tube and door assembly, whereby said door shields the

interior of said housing after said fuse link has blown.

4. A fuse construction comprising a housing, a door for said housing, a fuse tube secured to said door, said housing having upper and lower stationary contacts and said fuse tube having an upper and a lower contact normally engaging the upper and lower stationary contacts, a fuse link within said fuse tube electrically connecting the upper and lower contacts of said fuse tube, and mechanism normally restrained by said fuse link for moving the lower portion of the fuse tube and door outwardly while maintaining the upper portion of the door in close relation to said housing and for limiting the outward motion of said door, said mechanism moving the lower contact of said fuse tube out of engagement with the lower stationary contact.

5. A fuse construction comprising a housing having stationary upper and lower contacts, a fuse tube and door assembly movably carried by said housing and adapted to tilt outwardly with the lower end of the door projecting outwardly and the upper end of the door remaining in relatively close relation to the housing, jointed lever mechanism for guiding the fuse tube and door assembly from normal position to the slanting position and limiting the motion of said assembly to hold said assembly in the slanting position, and a fuse link normally electrically connecting the upper and lower contacts and restraining said mechanism against motion, said assembly including a contact movable away from at least one of said stationary contacts when said fuse link has been ruptured and said assembly is held in slanting position.

6. A fuse construction comprising a housing having upper and lower stationary contacts, a fuse tube and door assembly whose lower portion is movable outwardly with reference to said housing while the upper portion remains adjacent said housing to cause said assembly to occupy a slanting position with reference to said housing, mechanism for guiding and moving said assembly to the slanting position and holding said assembly in the slanting position, said assembly having a movable contact normally engaging the lower stationary contact and moving away from the lower stationary contact when said assembly moves to the slanting position, and a fuse link within said fuse tube normally restraining said mechanism and electrically connecting the upper stationary contact with said movable contact.

7. A fuse construction comprising a housing having stationary upper and lower contacts and having a lower support, a fuse tube and door assembly, said fuse tube having an upper contact normally engaging said upper stationary contact and having a lower contact normally engaging the lower stationary contact, a lever pivoted on said support and slidably and pivotally connected to said fuse tube for guiding the lower end of said fuse tube and door assembly outwardly with reference to said housing while the upper end of said fuse tube and door assembly remain in close proximity to said housing and for moving the lower contact of said fuse tube away from said lower stationary contact, a fuse link normally restraining said lever and electrically connecting the upper and lower contacts of said fuse tube, and means for limiting the outward motion of said fuse tube and door assembly while the upper portion of said assembly remains in close proximity to said housing.

8. A fuse construction comprising a housing

having stationary upper and lower contacts and having a lower support, a fuse tube and door assembly, said fuse tube having an upper contact normally engaging said upper stationary contact and having a lower contact normally engaging the lower stationary contact, a lever pivoted on said support and slidably and pivotally connected to said fuse tube for guiding the lower end of said fuse tube and door assembly outwardly with reference to said housing while the upper end of said fuse tube and door assembly remain in close proximity to said housing and for moving the lower contact of said fuse tube away from said lower stationary contact, a fuse link normally restraining said lever and electrically connecting the upper and lower contacts of said fuse tube, and means for limiting the outward motion of said fuse tube and door assembly while the upper portion of said assembly remains in close proximity to said housing, said lower support being electrically dead after outward motion of said assembly.

9. A fuse construction comprising a housing having stationary upper and lower contacts, a fuse tube having at least a lower contact normally engaging the lower stationary contact, a one piece door forming an assembly with said fuse tube, mechanism for restraining the upper end of said door and fuse tube assembly from outward motion and for moving the lower end of said fuse tube and door assembly outwardly to cause said assembly to assume a slanting position, and a fuse link electrically connecting the upper stationary contact and the lower contact of said fuse tube and normally restraining said mechanism, said mechanism including a stop permanently carried by said fuse tube and holding said assembly in the slanting position after rupture of said fuse link.

10. A fuse construction comprising a housing having upper and lower contacts and a lower support, a fuse tube and door assembly, a lever pivoted upon said support and having a slotted upper end, a pin carried by said assembly and located within the slotted upper end of said lever, a spring urged contact finger pivotally carried by said assembly and normally engaging the lower stationary contact, said fuse tube having an upper contact normally restrained against outward motion by the upper stationary contact, said upper stationary contact including spring means urging said fuse tube and door assembly outward, means limiting the rocking motion of said lever relative to said fuse tube and preventing said fuse tube from disengaging the upper stationary contact, and a fuse link connecting said contact finger and the upper contact of said fuse tube and restraining said lever, said lever having a stop normally limiting the outward motion of said contact finger when said fuse link is intact and moving out of the way of said contact finger upon rupture of said fuse link.

11. A fuse construction comprising a casing having upper and lower stationary contacts and having a lower support separate from said lower stationary contact, a fuse tube and door assembly, said fuse tube having a fuse link therein normally electrically connected to said upper stationary contact, a contact finger normally engaging said lower stationary contact and electrically connected to said fuse link, a lever pivoted upon said lower support and pivoted to said fuse tube for moving the lower portion of the fuse tube and door assembly outwardly a limited distance upon rupture of the fuse link, said fuse link normally

restraining the movement of said lever, means for holding the upper portion of said fuse tube and door assembly to said casing after said lever has moved the lower portion of said assembly outwardly, and a stop rigidly carried by said fuse tube and limiting the rocking motion of said lever relative to said fuse tube.

12. A fuse construction comprising a casing having upper and lower stationary contacts and having a lower support separate from said lower stationary contact, a fuse tube and door assembly, said fuse tube having a fuse link therein normally electrically connected to said upper stationary contact, a contact finger normally engaging said lower stationary contact and electrically connected to said fuse link, a lever pivoted upon said lower support and pivoted to said fuse tube for moving the lower portion of the fuse tube and door assembly outwardly a limited distance upon rupture of the fuse link, said fuse link normally restraining the movement of said lever, and means for holding the upper portion of said fuse tube and door assembly to said casing after said lever has moved the lower portion of said assembly outwardly, said contact finger moving away from said lower stationary contact due to the movement of the assembly outwardly the said limited distance.

13. A fuse construction comprising a casing having upper and lower stationary contacts and having a lower support separate from said lower stationary contact, a fuse tube and door assembly, said fuse tube having a fuse link therein normally electrically connected to said upper stationary contact, a contact finger normally engaging said lower stationary contact and electrically connected to said fuse link, a lever pivoted upon said lower support and pivoted to said fuse tube for moving the lower portion of the fuse tube and door assembly outwardly a limited distance upon rupture of the fuse link, said fuse link normally restraining the movement of said lever, and means for holding the upper portion of said fuse tube and door assembly to said casing after said lever has moved the lower portion of said assembly outwardly, said contact finger moving away from said lower stationary contact and said lower support being electrically dead upon movement of the assembly the said limited distance.

14. A fuse construction comprising a housing having an upper and a lower stationary contact and having a lower support, a fuse tube having upper and lower contacts engaging the upper and lower stationary contacts respectively, a fuse link within said fuse tube joining the upper and lower contacts of said fuse tube, a lever pivotally mounted on said support and on said fuse tube and being normally restrained by said fuse link, said fuse tube being movable outwardly adjacent its lower portion upon rupture of said fuse link, and means carried by said fuse tube and normally out of engagement with said lever for limiting the outward motion of said fuse tube to maintain contact between the upper contact of said fuse tube and the upper stationary contact.

15. A fuse construction comprising a housing having stationary upper and lower contacts and having a lower support, a fuse tube and door assembly, said fuse tube having an upper contact normally engaging said upper stationary contact and having a lower contact normally engaging the lower stationary contact and including a spring pressed contact lever carried by said fuse tube, a lever pivoted on said support and piv-

totally connected to said fuse tube for guiding the lower end of said fuse tube and door assembly outwardly with reference to said housing while the upper end of said fuse tube and door assembly remains in close proximity to said housing, said spring pressed contact lever remaining in contact with said lower stationary contact for a material portion of the movement of the lower end of said fuse tube and door assembly outwardly and moving away from said lower stationary contact upon completion of the outward mo-

5 tion of the lower portion of said fuse tube and door assembly, a fuse link normally restraining said lever and electrically connecting the upper and lower contacts of said fuse tube, and means for limiting the outward motion of aid fuse tube and door assembly while the upper portion of said assembly remains in close proximity to said housing.

WILLIAM O. SCHULTZ.
